UNITED STATES PATENT OFFICE.

HENRY J. BRODERSON AND WILLIAM E. BARTELS, OF WHITING, INDIANA, ASSIGNEES TO STANDARD OIL COMPANY, OF WHITING, INDIANA, AND CHICAGO, ILLINOIS, A CORPORATION OF INDIANA.

MIXING APPARATUS FOR TREATING OILS.

Application filed March 24, 1924. Serial No. 701,395.

The present invention relates to a mixing apparatus for use in connection with the refining of oils, and particularly light mineral oils such as kerosene, gasoline and like distillate products. It will be fully understood from the following description, illustrated by the accompanying drawings, in which:

Figure 1 is a view, partly in section, showing apparatus constructed in accordance with the invention; and

Fig. 2 is a sectional view through the dispersing device shown in Fig. 1.

In many cases, in the treating of light mineral oil it has been found advantageous to employ relatively minute amounts of an immiscible or partly miscible treating reagent; for example, in proportions of one to two pounds of treating reagent per barrel of the liquid treated. The proper admixture of the liquid to be treated with such minute amounts of the treating reagent has been found very difficult, inasmuch as the treating reagent tends to react with a small proportion of the oil, the particles of the treating reagent becoming coated with reaction products and leaving the greater portion of the liquid untreated. By means of the apparatus of this invention, a thorough, intimate homogeneous admixture of minute amounts of the treating reagent may be effected, thus producing a uniform and adequate treatment of the entire batch.

Referring more particularly to the drawings, the numeral 5 indicates a conduit through which the liquid to be treated passes, this conduit being provided with a suitable valve 6, shown partly broken away. From the line 5, on one side of the valve 6, a line 7 is brought around to the other side of the valve 6, this line 7 hereinafter designated the mixing conduit, being provided with a control valve 8. Beyond the connection of the mixing conduit 7 with the line 5 there are provided in the latter a number of orifice plates 8^a, this portion of the line 5 operating as an orifice mixer.

Within the mixing conduit 7, before it connects with the line 5, there is provided a dispersing device shown in side elevation in Fig. 1 and in section in Fig. 2. This dispersing device is so constructed as to finely atomize the treating reagent and distribute it in a direction substantially transverse to the movement of the oil passing through

the line 7, which is indicated by arrows in Fig. 1. The dispersing device is formed with a chamber 9, provided at one end with a perforation through its wall, this perforation being preferably conical in form. Within the chamber is provided a conical valve 11, slightly smaller at its smallest portion than the orifice 10, and connected to it is a reverse conical portion 12 exteriorly of the chamber 9. A threaded valve stem 13 is connected to the valve member 11 and extends through a threaded opening in the opposite end 14 of the chamber 9. The valve stem extends through the wall of the conduit 7 and is provided externally thereof with a suitable valve head 15, by rotation of which the valve portion 11 and with it the external conical portion 12 may be moved inwardly or outwardly to enlarge or decrease the size of the opening 10. A supply pipe 16 for the treating reagent passes through the wall of the conduit 7 and communicates with the interior of the chamber 9.

In operation the liquid to be treated is caused to flow through the mixing conduit 7 by closing the valve 6 and opening the valve 8. The treating reagent is forced into the conduit through the pipe 16, entering the chamber 9 and being atomized in its passage through the opening 10, the effective size of which is controlled by the valve member 11. The atomized and finely dispersed treating reagent is then forced outwardly transverse to the current of the liquid flowing through the mixing conduit by the action of the reverse conical element 12, which may, if desired, be provided at its end with an outwardly extending flange 20. The proportion of treating reagent is controlled by suitable manipulation of the valve 15, and an intimate and uniform admixture of the treating reagent with the liquid is thereby produced. The mixture of liquid and treating reagent is caused to return to the conduit 5 and is forced through the orifice plates 8^a, the mixing operation being thereby continued.

We claim:

1. In a mixing device, a conduit through which material to be treated flows, a hollow head within said conduit having an opening directed in the direction of flow of liquid through the conduit, a valve member within said head for controlling the size of the

- opening and a conical member secured to said valve member exteriorly of the head and larger than the opening for controlling the direction of flow of material passing through said opening and means for supplying a treating reagent to the interior of said head.
2. In apparatus for mixing minute quantities of a treating reagent with a liquid to be treated, a conduit through which the liquid to be treated flows, a mixing head within said conduit, said head having an opening directed in the direction of flow of the liquid, a conical valve member within said head for controlling the size of the opening and a reverse conical member exteriorly of the opening and connected to the conical valve member for controlling the direction of flow of liquid leaving the head, and means for introducing a treating reagent into said head.
3. In apparatus for mixing minute quantities of a treating reagent with a liquid to be treated, a conduit through which the liquid to be treated flows, a head within said conduit and having an opening directed in the direction of flow of liquid to be treated, a conical valve member within said head for

controlling the effective size of the opening, a reverse conical valve member within said head for controlling the admixive size of the opening, a reverse conical member exteriorly of the head and connected to the conical valve member, said reverse conical member having an outwardly directed flange at its outer end, and means for introducing the treating reagent into said mixing head.

4. An apparatus for mixing minute quantities of a treating liquid with a liquid to be treated comprising a conduit through which the liquid to be treated flows, a head within said conduit having an opening directed in the direction of flow of the liquid to be treated, a valve adapted to be fixed in spaced relationship to said opening, means extending through the wall of said conduit for adjusting said valve, spreading means adjacent to said opening and without said head for the purpose of directing the treating liquid substantially across the flow of the liquid under treatment, and means extending through the wall of said conduit for supplying liquid reagent to said head.
